(57) **CLAIM**

The ornamental design for a tool for holding an S-cam brake, as shown and described.

DESCRIPTION

FIG. 1 is a perspective view of a tool for holding an S-cam brake showing my new design;

FIG. 2 is a front view of the tool of FIG. 1;

FIG. 3 is a side elevation view of FIG. 2;

FIG. 4 is a bottom view of FIG. 2; and,

FIG. 5 is a top view of FIG. 2.

The S-cam brake shown by the dashed lines in FIG. 1 is for illustrating purposes and form no part of the claimed invention.
